ATTORNEYS.

UNITED STATES PATENT OFFICE

HANS PETER LUHN, OF WYOMISSING, PENNSYLVANIA, ASSIGNOR TO BERKSHIRE KNITTING MILLS, OF WYOMISSING, PENNSYLVANIA, A CORPORATION OF PENNSYLVANIA

ORNAMENTED FLAT-KNITTED STOCKING

Application filed October 28, 1929. Serial No. 402,821.

My invention relates particularly to the manufacture of flat-knitted stockings provided with ornamental figuring, and my object is to enable improved embodiment of such ornamental thread effects in close proximity to the seaming edges of the fabric; as fully described in connection with the accompanying drawing, and clearly defined in the subjoined claims.

10 Fig. 1 indicates a flat-knitted stocking fabric as made in accordance with my invention; the normal seaming edge showing supporting lateral extensions added on to it, and ornamental figuring being indicated adjacent

15 thereto;

Fig. 2 indicates the fabric after usual seaming thereof to form a tubular stocking; the supporting fabric extensions shown on Fig. 1 having been removed.

20 In my improved method of manufacture, the knitting may be continuously done upon usual straight or full-fashioned knitting machines, with such slight modification of the ordinary knitting operation as will be readily

25 understood by those skilled in the art: the knitting of the main fabric being effected as usual upon a straight series of needles to which the threads are fed as desired by controlled thread carriers and the number of 30 which is automatically varied by so called narrowing and widening mechanism for shaping of the fabric, and additional needles and threads being added in known manner to effect the purpose of my invention.

35 The flat fabric thus ordinarily produced is knitted with selvage edges 10, 10, and may be provided with desired ornamental figuring, either during the process of knitting or by a subsequent embroidering operation.

40 My invention consists only in providing for more satisfactorily effecting such ornamentation by temporarily adding to the width of the knitted fabric, as hereinafter fully described.

45 It is frequently desirable that the ornamental figuring which is provided on full-fashioned stockings be extended as close as possible to the seaming edge of the flat-knitted fabric. To accomplish this satisfactorily it 50 is necessary that such edge portion be held

in proper position laterally during the ornamenting operation; and to this end my invention consists in adding onto such edge portions of the fabric temporary fabric-extensions thereof as indicated at 15, 15, whereby the 55 normal edge portions 10 are held just as satisfactorily as is the rest of the fabric during the ornamenting operation; the advantage of such edge-supporting fabric extensions being especially obvious when ornamenting thread 60 is embodied in the knitted fabric by a subsequent embroidering operation, in which case the temporary fabric extensions provide most needed support to the normal edges of 65 the fabric; though like advantage is in some cases secured by the providing of such extensions simultaneously with the knitting-in of adjacent ornamentation. In either case these extensions are removed subsequent to the production of the ornamented fabric, as the 70 seaming is effected at the normal edges of the fabric; and a separate inexpensive thread may ordinarily be employed to advantage in producing such temporary extensions.

75 What I claim is:

1. The improved method of manufacturing flat-knitted stockings provided with ornamental figure effects, which consists in knitting supporting lateral extensions onto normal edge portions of the fabric to facilitate 80 the production of such figure effects close to said knitting edge portions, and thereafter removing said lateral extensions and seaming the edges.

2. The improved method of manufacturing flat-knitted stockings provided with ornamental figure effects, which consists in knitting supporting lateral extensions formed of different threads onto normal edge portions 90 of the fabric to facilitate the production of such figure effects close to said knitting edge portions, and thereafter removing said lateral extensions and seaming the edges.

95 In testimony whereof I affix my signature.

HANS PETER LUHN.
